UNITED STATES PATENT OFFICE.

EDGAR W. BROWN, OF DAYTON, OHIO.

DESIGN FOR AN AIR-DEFLECTOR FOR ELECTRIC FANS.

SPECIFICATION forming part of Design No. 31,900, dated November 28, 1899.

Application filed October 30, 1899. Serial No. 736,314. Term of patent 7 years.

To all whom it may concern:

Be it known that I, EDGAR W. BROWN, a citizen of the United States, residing at Dayton, in the county of Montgomery and State of Ohio, have invented and produced a new and original Design for an Air-Deflector for Electric Fans; and I do declare the following to be a full, clear, and exact description of the same, reference being had to the accompanying drawings, forming a part thereof.

Figure 1 is a plan view of an air-deflector for electric fans made in accordance with my design. Fig. 2 is an elevation of the same.

As shown in the drawings, the leading or

material features of my design consist of a 15 circular shell or casing having the form in side elevation of a truncated cone, the wall A of which is concavo-convex uniformly throughout, the concave surface being outward.

Having described my invention, I claim— 20

The design for an air-deflector for electric fans, substantially as shown and described.

In testimony whereof I affix my signature in presence of two witnesses.

EDGAR W. BROWN.

Witnesses:

R. J. McCARTY,

CARL NOE.
